UNITED STATES PATENT OFFICE.

THOMAS A. DE VILBISS, OF TOLEDO, OHIO, ASSIGNOR TO THE DE VILBISS COMPANY, OF TOLEDO, OHIO, A CORPORATION OF OHIO.

DESIGN FOR A TRAY OR SIMILAR ARTICLE.

Application filed October 10, 1928. Serial No. 28,449. Term of patent 7 years.

To all whom it may concern:

Be it known that I, THOMAS A. DE VILBISS, a citizen of the United States, residing at Toledo, in the county of Lucas and State of Ohio, have invented a new, original, and ornamental Design for a Tray or Similar Article, of which the following is a specification, reference being had to the accompanying drawing, forming a part thereof.

I claim:

The ornamental design for a tray or similar article, substantially as shown.

THOMAS A. DE VILBISS.
